UNITED STATES PATENT OFFICE.

SAMUEL J. DUNKLEY, OF KALAMAZOO, MICHIGAN, ASSIGNOR TO DUNKLEY COMPANY, OF CHICAGO, ILLINOIS, A CORPORATION OF ILLINOIS.

CHERRY-PITTING MACHINE.

974,759.

Specification of Letters Patent.

Patented Nov. 1, 1910.

Application filed November 29, 1904. Serial No. 234,716.

To all whom it may concern:

Be it known that I, SAMUEL J. DUNKLEY, a citizen of the United States, residing in Kalamazoo, in the county of Kalamazoo and State of Michigan, have invented a new and useful Improvement in Cherry-Pitting Machines, of which the following is a specification.

My invention relates to improvements in cherry pitting machines.

The object of my invention is to provide a machine of a simple, efficient and durable construction, by means of which cherries may be automatically pitted and very rapidly and cheaply, and the pits separated from the cherries without waste or disfigurement or mutilation of the cherries, beyond the extent necessary for expulsion of the pits or stones.

It further consists in the novel construction of parts and devices and in the novel combinations of parts and devices herein shown or described, as claimed.

In the accompanying drawing, forming a part of this specification, Figure 1 is a front elevation of an automatic cherry pitting machine embodying my invention; Fig. 2 is a cross section on line 2-2 of Fig. 1; Fig. 3 is an end view; Fig. 4 is a detail vertical section through the drum; Fig. 5 is an enlarged horizontal section through the drum; Fig. 6 is an enlarged detail partial vertical cross section through the drum and stripper inside the drum; Fig. 7 is a detail plan view of the stripper; Figs. 8 and 9 are detail views of one of the pitting plungers.

In the drawing A represents the frame of the machine, B is an intermittently revolving hollow cylindrical drum, having a closed head or plate B¹ at one end and a rim B², furnished with ratchet teeth B³ for intermittently rotating the drum. The drum B is journaled and supported at one end on a stationary horizontal or nonrevolving shaft B⁴, said shaft being connected to the uprights A¹ A² of the frame at each end of the machine. The intermittently rotating hollow drum B is supported at its other and open end by anti-friction wheels or rollers B⁵ B⁶, which engage its periphery.

The drum B is provided on its periphery with a series of cherry receiving cavities b, preferably substantially semispherical in shape, and large enough to receive the largest cherries intended to be operated upon

by the machine. And each of these cavities b is furnished with a radial opening b¹ through the drum for the cherry pit and pitting plunger to pass through. The cherry receiving cavities b are arranged in a series of longitudinal rows b², there being preferably, as illustrated in the drawing, 16 cavities b in each row, so that 16 cherries may be simultaneously pitted at each stroke of the pitting plunger cross head.

D is the pitting plunger cross head, the same reciprocating in suitable guides a on the frame and provided with a plurality of pitting plungers D¹ secured thereto in a row and adapted to register with each row b² of cherry receiving cavities in the drum B as the drum rotates step by step. Each of the pitting plungers D¹ has a pitting head d furnished with a plurality of radial forks d¹, preferably four in number, and each having a sharp inclined cutting edge d², thus forming a sharp edged four pronged crotch to receive and engage the pit of the cherry.

The pitting plunger is formed with a relatively small shank and an enlarged head. This insures that the pit shall not be missed but shall be engaged and forced out; but the forward end of the head being formed with sharp cutting edges, and the shank of the plunger being small, the fruit is not crushed or lacerated. Each fork cuts through the top part of the cherry or other fruit without leaving an unsightly hole. The smaller shank follows down through the fruit and leaves it in as near a natural shape as is possible, without forcing out the pulp.

F is a stationary stripper, preferably of rubber or other elastic material, and supported and embraced inside the hollow drum B between a pair of supporting plates F¹ F², the upper one of which is preferably of sheet copper, so that the acid juices of the fruit will not cause the same to rust. The supporting plates F¹ F² are given a curvature in cross section corresponding to the inner periphery of the drum B, and the upper plate F² is arranged in close proximity to the inner periphery of the drum B. The rubber stripper plate F is provided with a series of sets of radial slits f, one set for each pitting plunger, and each set of slits preferably comprising four radial slits, corresponding to and registering with the

- sharp edges d^2 of the forks d^1 of the pitting plunger heads. The prongs or quadrants f^1 of the rubber stripper F between the radial slits f , thus fit in the notches d^3 between the forks or prongs d^1 of the pitting plunger head, and thus serve to strip and remove any pulp or material from the notches of the plunger head when the pitting plunger is retracted on its upstroke from the rubber stripper. The upper stripper guiding or supporting plate F^2 and the lower stripper supporting plate F^1 , have openings f^2 f^3 therein, one for each of the pitting plungers D.
- 15 G is a movable cross head carrying a series of cleaner or ejector plungers G^1 and mounted inside the drum to reciprocate on suitable stationary guides G^2 , and by means of which the pit discharging openings b^1 and b^2 and cherry cavities b in the drum are freed from pulp or other material which might otherwise adhere thereto.
- H is a stationary guard or scraper inside the drum for removing any materials adhering to the inner periphery of the drum.
- 25 K is a stationary trough supported inside the revolving drum beneath the stripper F, and pitting plungers.
- K^1 is an endless conveyer or device for re-
- 30 moving the pits from the receiving trough K, the same traveling on sprocket wheels or pulleys K^2 K^3 , one of which is located in the trough inside the drum.
- M is the stationary stripper above the
- 35 rotary drum, having holes or openings through which the pitting plungers reciprocate and serving to strip or free the forked heads d of the pitting plungers from pulp or material adhering thereto. The stripper
- 40 M is, preferably, of rubber and secured to a plate m.
- To cause the drum and each row of cherry receiving cavities therein to properly register with the pitting plungers, I provide the
- 45 drum with a series of registering guides b^3 , one in line with each row b^2 of cherry receiving cavities b ; and I provide the pitting plunger cross head D with a registering pin or guide d^4 to engage the guide hole b^3 in
- 50 the drum.
- The required movements may be communicated to each of the moving parts by any suitable mechanism, but I prefer to give the necessary intermittent or step by step movement to the drum by means of a ratchet B^3 on the drum, which is engaged by a pawl b^4 on the pawl lever b^5 , which is actuated by a crank or wrist pin p on the driving shaft P through the connecting link p^1 . The pitting plunger cross head D I prefer to reciprocate as required by means of cams or eccentricities P^1 P^1 on the driving shaft P and connecting straps P^2 P^2 . The cleaner or ejector plunger cross head G is preferably reciprocated as required by means of a rock
- shaft R inside the hollow drum B, having arms r connected to said cross head G, and an arm r^1 connected by a link r^2 to the pitting plunger cross head D. The rock shaft R is supported and journaled inside the hollow drum B on arms R^1 secured to the stationary shaft B^4 which extends through the drum. The guides G^2 for the cross head G are likewise supported inside the drum B by arms G^3 secured to the stationary shaft B^4 . And the supports F^1 F^2 for the stripper F are also supported and held stationary inside the hollow rotary drum B by arm G^3 secured to the stationary shaft B^4 , and the trough K to receive the pits is likewise supported on this stationary arm.
- T is the chute or hopper for holding the cherries in bulk, and causing them to automatically feed into and fill the cherry receiving cavities b of the drum B as it rotates.
- The operation is as follows: As the drum rotates intermittently the rows of cherry cavities b pass successively under the cherries in the cherry chute or hopper, and fill therewith, each cavity taking up a cherry. As each row of cavities is brought under the gang of pitting plungers the same descend, thus causing the sharp edged forked plungers to pass through the cherries and force the pits out thereof through the stripper F into the trough K; the pits being removed by the conveyer K^1 . Simultaneously with the movement of the pitting plunger D the cleaner or ejector plungers are also operated, thus keeping the cherry cavities and pit discharging openings free. As the drum B rotates the pitted cherries are conveyed around and discharged into a receiving pan or chute S.
- 105 I claim:
1. In a fruit pitting machine, the combination of means for holding the fruit, a pitting plunger having a relatively small shank, and an enlarged head divided into forks d^1 formed with sharp radial cutting edges d^2 on the end of the plunger, and an elastic stripper slotted to form yielding prongs which operate by their extremities passing between the forks, the slits of the stripper being in line respectively with the said cutting edges, substantially as set forth.
- 110 2. In a cherry pitting machine, the combination of means for holding the fruit, a reciprocating pitting plunger having a head furnished with a plurality of radial forks with inclined cutting edges, a rubber or elastic stripper having radial slits with stripping prongs between the radial slits, through which the pitting plunger may force the pit, upper and lower stationary curved supporting plates embracing the stripper, and suitable actuating mechanism, substantially as set forth.
- 115 3. In a cherry pitting machine, the com-

bination with an intermittently rotating hollow drum furnished with a series of rows of cherry receiving cavities, each having a pit discharge opening through the drum, of a 5 reciprocating pitting plunger cross head having a plurality of pitting plungers, each having a head furnished with a plurality of radial forks with inclined cutting edges, a rubber or elastic stripper having a series of 10 radial slits with stripping prongs between the radial slits through which the pitting plungers may force the pits, and upper and lower stationary curved supporting plates embracing the stripper inside said 15 drum, substantially as specified.

4. In a fruit pitting machine, the combination of means for holding the fruit, a reciprocating pitting plunger having a head furnished with a plurality of radial forks 20 with inclined cutting edges, an elastic stripper having radial slits with stripping prongs between the radial slits, through which the pitting plunger may force the pit, upper and lower stationary supporting plates embracing the stripper, and suitable actuating 25 mechanism, substantially as set forth.

5. In a cherry pitting machine, the combination with an intermittently rotating hollow drum, furnished with a series of cherry 30 receiving cavities, each having a pit discharge opening through the drum, of reciprocating pitting plungers, each having an enlarged head furnished with a plurality of forks with inclined faces, a stationary stripper 35 inside the drum, reciprocating cleaner or ejector plungers inside the drum, and a rock shaft inside the drum for operating said ejector plunger, substantially as specified.

6. In a cherry pitting machine, the combination of a non-rotary shaft, an intermittently rotating hollow drum mounted at one end on said shaft and furnished with fruit receiving cavities and pit discharging openings, reciprocating pitting plungers operating in such openings, a stationary stripper 45 inside the drum, a reciprocating cleaner inside the drum having a guiding connection with said shaft, and a rock shaft inside the drum for operating said cleaner, substantially as set forth. 50

7. In a cherry pitting machine, the combination with an intermittently rotating hollow drum, furnished with a series of cherry receiving cavities each having a pit discharge opening through the drum, of reciprocating pitting plungers, each having an enlarged head furnished with a plurality of forks with inclined edges, a stationary stripper inside the drum, and reciprocating cleaner or ejector plungers inside the drum, 55 substantially as described. 60

8. In a fruit pitting machine, the combination of means for holding the fruit, a pitting plunger having a relatively small shank and an enlarged head divided into forks formed 65 with radial edges on the end of the plunger and an elastic stripper slotted to form yielding prongs which operate by their extremities passing between the forks, substantially as described.
